UNITED STATES PATENT OFFICE

150,512

DESIGN FOR A TOBACCO HUMIDOR

Michael Pendriss, Burlington, Vt.

Application May 2, 1947, Serial No. 138,770

Term of patent 3½ years

(Cl. D85—2)

To all whom it may concern:

Be it known that I, Michael Pendriss, a citizen of the United States, residing at Burlington, in the county of Chittenden and State of Vermont, have invented a new, original, and ornamental Design for a Tobacco Humidor, of which the following is a specification, reference being had to the accompanying drawings, forming a part thereof.

Figure 1 is a side view of a tobacco humidor, showing my new design.

Figure 2 is a top plan view of the same.

Figure 3 is an elevational view of one end of the same.

Figure 4 is an elevational view of the opposite end of the same.

I claim:

The ornamental design for a tobacco humidor, as shown.

MICHAEL PENDRISS.
